TIME DELAY RELAY

Charles C. Ralph, Portland, Oreg.

Application August 11, 1934, Serial No. 739,390

1 Claim. (Cl. 200—97)

This invention relates generally to switching devices, and particularly to a time delay relay.

The main object of this invention is the construction of a thoroughly reliable and inexpensive time delay relay by means of which there may be interposed a definite lag in the opening or closing of one or more electrical circuits after the opening or closing of another circuit.

The second object is to provide a time delay relay which is independent of temperature conditions and which can be set with extreme accuracy.

The third object is the utilization of mercury in the switching element and the provision of means for protecting the mercury against oxidation under atmospheric and arcing conditions.

The fourth object is to utilize the well known affinity between mercury and certain other metals, such as copper, in order to obtain a rapid separation of the switching points when the circuit is broken.

The fifth object is to provide a construction which will improve the action of the solenoid.

The sixth object is to provide a form of relay adaptable for continuous use in controlling devices operated from ordinary lighting circuits.

These, and other objects, will become more apparent from the specification following as illustrated in the accompanying drawings, in which:

Fig. 1 is a diagrammatic view showing the manner of connecting a plurality of lights to the relay.

Fig. 2 is a vertical section through the preferred form of the device showing the relay closed.

Fig. 3 is similar to Fig. 2 but showing the relay open.

Fig. 4 is a vertical section through a modified form of the device employed for handling the current from a lighting circuit.

Fig. 5 is a side elevation of the rotor illustrated in Fig. 4, a portion of which is broken away in section and showing the circuit open.

Fig. 6 is similar to Fig. 5 but showing the rotor tilted and the circuit closed.

Fig. 7 is a vertical section through a simple form of the device showing the circuit closed.

Fig. 8 is similar to Fig. 7 showing the circuit about to be broken.

Fig. 9 is similar to Fig. 8 showing the circuit completely broken.

Fig. 10 is a view through a modification of the device in which it is used to operate a rheostat and in which the minimum amount of resistance is offered to the flow of current.

Fig. 11 is similar to Fig. 10 but showing the maximum amount of resistance offered to the flow of current.

Fig. 12 is a section through the point of a contact screw.

Similar numbers of reference refer to similar parts throughout the several views.

Referring in detail to the drawings, there is shown a tubular shell 12 of ferrous metal whose lower end 13 is of a similar material and has mounted on the center thereof a magnet core 14 whose upper end 15 extends through the floor 16 of insulating material which fits tightly within the shell 12 and forms a well for mercury 17.

Between the lower end 13 and the floor 16 and surrounding the core 14 is the electromagnet 18 to which current is supplied from a source of energy, such as a battery 19, through the lead wires 20. The flow of current to the magnet 18 is controlled by means of a switch 21 which may be either manually operated or responsive to time, temperature, or other conditions.

Within the shell 12 and floating in the mercury 17 is an open float 22 having a recess 23 in its top side. The float 22 is preferably provided with non-ferrous rings 24 and 25 which hold the float 22 out of intimate contact with the shell 12. Extending upwardly through the ring 24 and into the float 22 are the vertical holes 26 which communicate by means of the inclined holes 27 with the recess 23.

In the bottom 28 of the float 22 is mounted a bushing 29 made of copper, or some other suitable metal, and having a hole 30 formed therethrough.

The top of the shell 12 is closed by means of a head 31 of insulating material in which are mounted various contact screws 32, 33, 34, 35, 36, 37 and 38, the lower end of each of which is provided with a copper tip 39 (as shown in Fig. 12).

It will be seen in Fig. 1 that the contact screws 32, 33, 34 and 35 inclusive are connected to the lamps 40, 41, 42 and 43. This, however, is merely for the purpose of illustration since they are capable of being connected in any other manner desired, and the screws 36 to 38 may be connected to other lamps or apparatus if desired. The lamps 40 to 43 are connected to the battery 19. The battery 19 is also connected by means of a wire 44 to the bottom end 13.

The operation of this form of the device is as follows: Assuming that the switch 21 is closed, either manually or automatically, as the result of a thermostatic action, or by a time switching

mechanism, or in any other manner which will permit current to flow to the magnet 18, thus overcoming the balance of buoyancy of the float 22 and submerging it in the mercury 17, forcing the mercury up through the holes 26, then through the holes 27 into the recess 23, some of the mercury also passing upwardly through the small hole 30.

The submerging of the float 22 has brought about a rise in the level of the mercury 17 which now surrounds the lower ends of the screws 32 to 36. It will be understood that the float 22 is in reality the armature for the magnet 18 and will descend when the magnet 18 is energized, or rise to a floating position when the magnet 18 is not energized.

The various lamps 40 to 43 will remain lighted as long as the switch 21 remains closed, and in addition thereto until the mercury 17 has had time to pass downwardly through the small opening 30, thereby permitting the float 22 to rise and displace less of the mercury thereby uncovering the various screw points 39 in the order of their elevation—that is, the highest point 36 for example, will be uncovered first and the lowest point 32 will be uncovered last.

It will be observed that the rapidity of the operation is controlled to a large extent by the size of the openings 26, 27 and 30, while the timing may be accurately controlled by the setting of the various screws 33 to 36.

In the form of the device shown in Figs. 4 to 6 the same armature or float 22 is employed, as well as the magnet 18 and shell 12. With this form of the device, however, is employed a gas filled or evacuated sphere 45 which is rockably mounted on the metallic trunnions 46 which journal in the brackets 47 and 48, which are separately mounted on the under side of the head 49 made of insulating material.

The brackets 47 and 48 are joined by the wires 50 and 51 to a motor 52 which is connected to a power circuit 53. Within the sphere 45 is a dam 54 which, like the sphere 45, is made of an insulating material such as glass. The dam 54 is normal to the axis of the trunnions 46.

Connected to the trunnions 46 and extending into the sphere 45 are the electrodes 55 which extend almost to the dam 54, somewhat near one end thereof. A trunnion 46 is provided with a crank 56 which is joined by a connecting rod 57 to an eye 58 secured to the float 22, preferably near the middle thereof.

The operation of this form of the device is as follows: When the switch 59 is closed and the float 22 submerged the sphere 45 is rocked on its axis to the position shown in Fig. 6, permitting current to flow between the electrodes 55 through the mercury 60, however when the switch 59 is again opened and when enough mercury 17 has passed downwardly through the hole 38, thereby permitting the float or armature 22 to rise, then the sphere 45 is returned to its original position (as shown in Fig. 5).

The point to be observed here is that when the break in the circuit is made it occurs from the dam 54, and this break is very rapid and a very small amount of power is required to rock the sphere 45 as compared with the mercury switches of the tilting tube type.

In the form of the device shown in Figs. 7 to 9 a simple form of float or armature 61 is illustrated and there is provided sufficient clear-

ance 62 around the float 61 to permit the rapid upward movement of the mercury 17. In this form of the device a single electrode screw 63 is illustrated, and there is also shown the use of the oil film 64 on the surface of the mercury 17, the purpose of which is to reduce oxidation either from atmospheric conditions or from arcing conditions.

It will be noted that the screw 63 is provided with a copper tip 39 whose affinity for the mercury 17 causes it to form a connecting column 65 (as shown in Fig. 8); however, when the column 65 has reached its maximum length it severs very rapidly, bringing about a very desirable action for the circuit breaker. 15

In the form of the device shown in Figs. 10 and 11 instead of employing the contact screws 32 to 38 or the rockable sphere 45, there is illustrated the use of a rheostat which consists of a simple resistance coil 66 which is suspended from 20 the head 67 by means of the screws 68 and 69.

It can be seen that in this form of the device the flow of current to the lamp 70 may be variably controlled, since the resistance offered by the element 66 is effected by the amount which 25 is shorted out by the mercury 17.

It will be noted that plug 29 is preferably made of copper or some metal which will amalgamate with mercury and this plug has a small hole 30 drilled therethrough. The side of this 30 hole amalgamates with the mercury and offers a capillary attraction which aids in the flow of mercury through the hole, thus permitting the use of a very minute hole that is at all times covered with mercury preventing any possibility 35 of foreign substances clogging the hole.

The use of this plug increases the efficiency of the device by allowing delays on a small relay up to five minutes, whereas the greatest possible delay without the amalgamating plug will be 40 about five seconds.

The amalgamated tip 39 allows a delay on the return of the armature to its floating position. This feature of the relay makes it automatic in action whereby it will cause a continuous recycling action of the armature with a predetermined time delay both on the closing and the opening of the circuit. 45

In other words, it is the combined action of the amalgamated plug and the amalgamated tip 50 which makes possible the abnormally long delay interval obtainable with this relay.

I claim:

A time delay relay comprising a mercury bath, 55 an armature in the form of a container adapted to float in said bath, said armature having an opening in the bottom thereof through which mercury can pass to or from the interior of the armature, an electromagnet associated with said armature for exerting a pull thereon for the purpose of submerging said armature, the emerging action being retarded by the flow of mercury through said opening and a mercurial switch in the form of a sphere rockably mounted 60 on a horizontal axis and having a dam across the lower portion thereof normal to its axis, said switch having spaced electrodes therein separated by said dam and having a body of mercury confined within said sphere, together with 65 means for rocking said sphere to conform with the movements of said armature. 70
